(57) **CLAIM**

The ornamental design for a light fixture, as shown and
described.

DESCRIPTION

FIG. 1 is a front perspective view of the light fixture
comprising my new design;

FIG. 2 is a front elevational view thereof;

FIG. 3 is a side elevational view thereof which is an identical
mirror image of the other side;

FIG. 4 is a back elevational view thereof;

FIG. 5 is a top plan view thereof; and,

FIG. 6 is a bottom plan view thereof.

FIG. 1-FIG. 6 showing chains of translucent crystals defining
arcs in space and crystal drop ornamentation.

The broken lines shown are for illustrative purposes only
and form no part of the claimed design.
